Specification of Letters Patent.

Patented Sept. 2, 1919.

Application filed February 2, 1910, Serial No. 541,490. Renewed March 26, 1914. Serial No. 827,499.

To all whom it may concern:

Be it known that we, HERBERT S. HANSON and CHARLES M. UPHAM, citizens of the United States, residing at Peoria, in the county of Peoria and State of Illinois, have invented certain new and useful Improvements in Gang-Plows; and we do hereby declare that the following is a full, clear, and exact description of the invention, which 10 will enable others skilled in the art to which it appertains to make and use the same.

This invention relates to gang plowing mechanisms of the class in which each is self contained and adapted to be readily attached 15 to and detached from a suitable tractor device.

The plowing mechanisms of this class, proposed prior to our invention, were usually of one or the other of two distinct 20 types. Each of the mechanisms of one type comprised a frame, plowing units connected to the frame (usually trailing behind it), plow supports on the frame (usually heavy cantaliver devices projecting rearward 25 therefrom above the units), and means connected to the units and engaging the supports for bodily lifting the units from the ground. Each of the mechanisms of the other type comprised a frame, plowing units 30 trailing behind the frame, ground wheels connected respectively to the units and serving to support them each independently of the others in fixed relation to the ground, and manual means whereby an operator 35 standing on the platform could apply power to move the plowing units up and down relatively to the respective ground wheels as abutments.

Plows of the first type were found to be 40 seriously objectionable because of the great weight of the rearward projecting cantaliver supports and the necessary corresponding great weight of the main frame, because of the fact that the plowing units were so 45 supported that they were not permitted to follow closely the irregularities of the ground, and because of other difficulties. Plowing mechanisms of the second type were found to be much superior to those of the 50 first type, but they were nevertheless far from satisfactory because of the heavy manual labor required to raise and lower the plowing units, and because of the difficulty in causing the plows to leave or enter the

ground at the same transverse line. During 55 operation each plowing unit was locked with respect to its wheel and when the plows were to be raised it was necessary for a plowman (or sometimes two or three plowmen) on the platform of the frame to first unlock the units from the wheels and then by manual effort to bodily move the units upward with respect to the wheels.

By our invention we have provided a 60 plowing mechanism having all of the advantages incident to the plows of the sort comprising the second said group, and we have obviated the disadvantages and difficulties heretofore incident to plowing mechanisms of this sort. We have provided means 65 under the control of the operator whereby mechanical power derived from a single unitary motive means, which is in its entirety mounted upon or secured to the main frame, can be transmitted and applied to cause relative movement between the plowing units and the respective wheels thereby lifting the units with respect to the ground. Furthermore by our invention we provide for the 70 lifting or lowering of the plows successively beginning with the foremost one, thus causing them to leave or enter the ground at the same transverse line.

The principal object of our invention is 75 to provide means whereby the power of a unitary power mechanism can be transmitted to the ground wheels of the several plowing units to move them successively with respect to their units to cause the units to be 80 lifted successively. Other objects are to provide certain improved structural features 85 which will be apparent from the following 90 specification and claims.

In the accompanying drawing:—

Figure 1 is a plan of a gang plow embodying our invention. Fig. 2 is a front elevation of the ground wheel and associated parts for one of the plowing units. Fig. 3 is a side elevation of the gang plow shown on a much larger scale than in Fig. 1, with 100 but one plowing unit illustrated. Fig. 4 is a plan of certain portions shown in Figs. 1 and 3 but on a greatly enlarged scale. Fig. 5 is a transverse section of a supporting shaft showing a certain lifting member carried thereby. Fig. 6 is a similar view showing the lifting member at another extreme 105 position. Fig. 7 shows, in perspective, a

series of the parts illustrated in Figs. 5 and 6. Fig. 8 is a similar view showing one of the members in a position intermediate the extreme positions shown in Figs. 5 and 7.

5 The frame or platform of the plow is indicated by the letter A, it being constructed of certain framing parts which are not shown since they are not involved in the present invention. As shown in Fig. 1 the 10 frame is triangular in form and has draft devices B of any suitable form by means of which it can be detachably connected to a suitable tractor. The frame is mounted upon ground wheels C, there being one 15 shown at D at the rear, said wheels being mounted in any suitable or preferred way. The rear portion of the platform is inclined at an angle to the line of advance, as in other machines of this type, and at intervals 20 thereon there are secured rearwardly extending brackets E to each of which is pivotally attached a plowing unit comprising a plow beam F and a plow body G secured to the rear thereof. There are also 25 brackets H, similar to the brackets E, to which a supplemental beam J is pivoted, both beams being connected at their rear ends in any suitable manner. It will be seen that by this construction we have provided 30 for each plowing unit a transverse horizontal pivotal connection to the main frame which is fixed against vertical movement, the unit being free to swing vertically in a fixed path about the axis of the connection. Each plowing unit is supported from 35 the ground by means of its own individual ground wheel with which it is connected in such a way that relative vertical movement is possible. As before stated plowing units 40 thus supported are well known and we do not claim this feature broadly as a part of our invention. The particular form of connection between the wheel and the beam which we have shown and which is described 45 below is selected merely for purposes of illustration and it will be understood that changes may be made as to the details. To the beams F and J, respectively, (see Fig. 2) are attached brackets K both forming 50 guides for two vertically disposed arms L mounted at their lower ends on a ground wheel M. The said brackets serve to hold the standards L in vertical positions and to guide them for vertical movement. Pivoted 55 to each standard L is an arm or link N and between the upper ends of the links is mounted a bell-crank lever O, one arm of said lever having pivotal attachment to the beam F, through a standard P, the other arm having 60 pivotal connection with a power transmitter or reach Q to be hereinafter described.

It will be noted that in Fig. 3 the plowing 65 unit is shown at its working depth and that the lever O is in a rearward position. If the upper arm of the lever is moved forward

to the position indicated in broken lines in Fig. 3, the lower arm will be raised and at the same time the arms N in which the lever is hung will move forward. Inasmuch as the plowing unit is connected to the lower 70 arm of the lever O by means of the standard P the result is that the plowing unit is lifted from the ground. As long as the upper arm of said lever O is held in its forward position the plow will be sustained in the raised 75 position. Mounted upon or at least connected to the frame of the plow is a power mechanism which controls the plowing units by means of the ground wheels and the connections therewith which have been 80 described. By preference we employ a shaft R which lies at right angles to the line of advance, and in the present instance it lies parallel to the front line of the frame. Upon one end of the shaft is mounted a 85 sleeve S, Figs. 4, 7 and 8, bored so as to be slipped upon the shaft. The sleeve may turn freely on the shaft, or the sleeve and the shaft may revolve together the latter merely acting as a support for the sleeve and 90 for other similar parts now to be described. The sleeve carries and is driven by a worm wheel S' and is provided at its extremity with an extension or lug T, shown in the figures named, and in cross section in Figs. 95 5 and 6. This lug may be of any desired length and is in the form of a quadrant equal in area to one-fourth of the cross sectional area of said sleeve. Adjacent to this sleeve is a similar sleeve U also loose on the 100 shaft but provided at one end with a lug V and at the other with a lug W both similar to said lug T and with the first of which said lug T is adapted to engage (see Figs. 5, 6 and 7). The lug W of the sleeve U is 105 likewise adapted to engage the lug X of a similar loose sleeve 2 which has at its opposite end a correspondingly placed lug 3 adapted to engage a similar lug 4 on still another sleeve Y, there being as many more 110 of the sleeves as there are plows to be operated. Upon each of the sleeves are two fixed lugs 5 and 6 placed substantially diametrically opposite one another, see Figs. 5 and 6. Upon each sleeve is rotatably 115 mounted what we shall term a crank-arm 7 which lies between the said lugs 5 and 6 and a journal-bearing Z shown in Fig. 1, the several bearings carrying the sleeves. The said journal-bearings are not shown in Figs. 120 7 and 8 since they would tend to confuse and would hide some of the other parts. At each side of the train of sleeves and their arms and lying substantially parallel to the shaft R is a stop, one being indicated at 8 125 and the other at 9, which receive and limit the movements of the arms which are adapted to turn upon their respective sleeves through substantially a half revolution, see the continuous and broken lines in Figs. 7 130

and 8. At one side of each arm 7 is a pair of pawls indicated by 10 and 11 each pivoted between its ends and each having at one of its ends a friction roller 12 adapted to engage a member 13 secured to some stationary part of the plow frame beneath each sleeve of the series and directly beneath said rollers. The upper surfaces of the members 13 are substantially concentric with the peripheries of the sleeves as shown and each has a flaring extension 14 at each end in order to lie in the path of the rollers. The adjacent ends of the pawls of each pair are connected by a spring 15 whose tendency at all times is to hold said ends toward the sleeve to which they lie adjacent. Any equivalent of this, however, may be otherwise placed in control of these ends of the pawls. Each of the arms 7 has attached to its extremity at the sides thereof links 16 as shown in broken lines in Fig. 5 and in full lines in Figs. 3 and 4. These links are curved or arched so as to reach over the sleeves and the journal-bearings, and they are attached at their rear ends to the power transmitters or reaches Q hereinbefore mentioned.

For driving the sleeve S and the various power transmitting elements with which it is mechanically connected, we provide a suitable motive means connected with the main frame so as to be bodily fixed with respect thereto. The motive means is a unitary one and has its parts all connected together so as to be operable only in fixed predetermined relation to each other; and the motive means is so mounted on the frame that each of its parts is operable only in fixed predetermined relation thereto. By mounting all of the parts of the motive means on the frame in the way described we are enabled to avoid any variation in the action of the motive means or of the power transmitters arising from relative movements between the frame and other parts, such as the traction engine, upon which a motive means might be mounted. Gang plows of this sort are frequently used on more or less rough and rolling land, and in such cases the positions of the plows would be affected at each variation of the relative positions of the main frame and tractor if the motive means were to be mounted on the tractor. Furthermore, by providing a unitary motive means having all of its parts connected together so as to operate in fixed predetermined relationship we obtain a relatively simple construction and insure the operation of the several power transmitters in the exact predetermined relationship. This relationship cannot be varied, as it would be were the several transmitters to be operated by separate elastic fluid motors, the operation of which would depend upon the amount of pressure, the amount of leakage, the amount of friction, etc. One form of motive means which is convenient and satisfactory under many conditions is shown and described. Mounted upon the platform A is a motor of any desired type such, for instance, as a steam or gasoline engine or an electrically driven device. In the present instance we represent an engine 17 having a crank shaft 18 provided with a pinion 19 to mesh with a gear 20 on a counter shaft 21 mounted in suitable bearings and lying at right angles to the shaft R and its sleeves before mentioned. Said shaft is provided, if desired, with a clutch of any one of the usual forms, indicated at 22, by which the gear wheel 20, which may be loose upon the shaft, may be coupled to said shaft, when desired, in order to drive it. Other ways, however, of forming the driving connection may be used, although the engine may be started and stopped in lieu of using the clutch. The shaft besides carrying the clutch has a worm 23 to engage the under edge of the worm wheel S'.

We desire to make it understood, however, that the motor may be made to drive some other form of gearing than that shown and described in order to transmit motion to the sleeve 3, the present form being merely a preferred one but it is the desire that no matter what form of gearing is used the motion imparted to the said sleeve shall be very slow as compared with that of the speed of the motor in order that the proper speed of revolution of the sleeve S and its companions will be definitely related to the speed of advance of the plow so that the intervals of time between the lifting of the several members of the latter will be correct. Since this speed of advance is practically uniform it is possible to so proportion the various gears that the proper intervals of time can elapse between the raising or lowering of the several plowing units. The speed of advance of the gang being known it is a simple matter to provide gears of the proper size to cause the plows to be lifted successively at each fourteen inches of advance, if that be the longitudinal distance between plow bodies.

When the parts are arranged substantially as described with the plow bodies at work in the ground as in Fig. 3 the arms 7 all lie at the rear of the shaft R and upon the stop 8 as shown in Fig. 7. The end of the field having been reached and the motor having previously been set in motion with the gear 20 running free, the clutch 22 is thrown into gear just before the first plow reaches the margin of the field. This locks the gear 20 to its shaft 21 and starts the revolution of the worm wheel S' and its sleeve S in a clockwise direction. The lug T of the sleeve which lies at the right side of the lug V of the sleeve U, as viewed in Fig. 7, must

now turn in the same direction until it meets the opposite or left side of the said lug V. The said sleeve U is now revolved until one of the lugs 5, 6 (see Fig. 6) meets the pawl 11 whose spring-held end lies against the sleeve in the path of said lug 5. In the continued motion the arm is lifted from its position shown in Figs. 3 and 7 and carried over to its other position upon the stop 9 as shown in Fig. 8. As the arm moves upward and forward its motion is transmitted through the power transmitter Q to the corresponding plowing unit and wheel, the unit being lifted by pressure exerted downward on the wheel. As the arm approaches its rearward position the friction roller 12 meets one of the extensions 14 of the member 13 and in following the curve thereof is moved nearer the sleeve U thus throwing its opposite end away from the sleeve and out of engagement with the said lug 5 or 6. The sleeve U is now free to turn on the shaft within the arm by the continued revolution of the worm-wheel. Substantially simultaneously with the disengagement of the first arm from the sleeve U, the lug W engages the lug X of the next sleeve 2 and one of the lugs 5, 6 thereon engages the pawl 11 on the next arm to move it and its attached parts in the way above described. The time elapsing between the movements of the two arms equals the time it has taken to advance the plow last raised to substantially the point at which the first one was cleared of the ground. The next action is to operate the sleeve 5 in the same way and so on throughout the entire train of sleeves and their arms 7 until all of the plows of the gang have been raised, the several lugs T, V, W, X, etc., being in continual engagement. As the several arms 7 are free of the sleeves the latter turn as a unit within said several arms, the lugs 5, 6 readily passing under the pawls 10 as they revolve with their respective sleeves, the pawls 11 meanwhile being held outward by the member 13 as described. The reaches Q hereinbefore mentioned are connected at their rear ends to the bell-crank levers O by two links Q', Fig. 1, while their other ends 50 are connected with the two links 16 before described and it is to be noted that the points of connection of the links 16 with the ends of the arms 7 lie below the center or axis of revolution of the said arms so that the line 55 of pull which extends through said points and the points of connection of the links Q' with the bell-crank levers O will be below said center or axis as indicated in the straight broken line in Fig. 5 and this serves 60 as a positive lock for the plows in the raised position. The degree of separation of the links 16 is such that the pawls 10 and 11 or the lugs 5 and 6 will not be interfered with.

65 After the last plow has been raised in the

manner described the apparatus is started back into the field, the motor having meanwhile been reversed, after having disengaged the clutch, so that as the starting line is reached with the clutch again thrown in, 70 the rotation of the worm-wheel and the sleeve S begin a reverse direction of movement or contrary clock-wise. The lug T is thus turned in that direction also and on engaging the lug V of the sleeve U one of the lugs 5, 6 of that member engages the pawl 10, which is always in position to receive it when the arm 7 lies in the position shown in Fig. 5, and lifts said arm until the line of pull from the plow is carried 75 above the axis of revolution of said arm. Having been thus released the plow immediately falls to its working position this being possible since the arm 7 controlling it is free to turn upon its sleeve thus carrying the engaging pawl 10 away from the lug 5, 6 which lifted it. In turning, the arm carries the pawl 10 with it and the roller 12 thereof immediately engages the member 13 thus moving said pawl out of 80 the path of the lugs 5, 6. During this time the entire apparatus has advanced until the point of the next plow reaches the proper position to be dropped and the sleeve U has turned far enough to engage the lug X of the sleeve 2 by its lug V and subsequently raises the arm 7 of that sleeve in the same way as before so that its plow is also dropped at the proper place. In this way the plows are dropped in successive 85 order at regular intervals at the starting line, until all are at work.

The shaft R plays no part in the operation of the mechanism whatever but serves merely to carry the sleeves and it is possible to use other forms of structures so as to eliminate it entirely as, for example, by merely extending the journal-bearings 2 so as to provide a perfect support throughout the greater part of the length of said sleeves. 105 Furthermore, the bearings and the parts supported thereby could be carried on some support or framing other than the platform A so long as such support or framing is fixed relative to the platform.

Each of the reaches Q, 16, is rigid throughout its length or between the points of connection with the crank-arm 7 and arm O, and as the parts 16 are curved they permit the point of connection with the arm 7 to 110 drop below the axis of the shaft R to form the lock as previously stated and this said part 16 may act as a limiting stop in one direction in lieu of the part 9 described, by resting upon the sleeve V, for instance.

We are aware that it has heretofore been proposed to provide for the uniform successive lifting of a plurality of plow units by means of power applied to the ground wheels which support the units, but in the 115 120 125 130

earlier devices with which we are familiar reliance was placed upon a plurality of independent motors, one for each plow and the effort was to so control these motors 5 that they would operate one after another in succession to move the ground wheels downward and thereby lift the plows. But there are serious objections to a plurality of motors, as there is no assurance that they 10 will operate at uniform intervals and at uniform speeds. One motor may be more efficient than another or may have less friction, or may be put into operation a little sooner or a little later than the others, and thus 15 disturb the proper timed relationship of the lifting. By our invention we have connected all of the unit supporting wheels to a single power mechanism and have interposed a power transmitting system which 20 is such that the power of the motive means is applied successively at fixed uniform intervals to move the wheels and effect the lifting.

We herein refer to the power generating 25 device as a "motor"; but do not limit ourselves to a gasoline motor of the form shown, as other motors for operating plow beams have been heretofore known, such as steam cylinders and pistons, and traction wheels 30 below the draft frame.

We also refer to prime power devices, these being typified in the construction shown and described by the rotary crank arms 7, but in lieu of which, as will be 35 understood, any suitable means can be used interposed between the motor element and the transmitting devices, such as the reaches or links Q, which actuate the devices that lift the plowing unit (beam and plow body) 40 from the ground.

Having thus described our invention, we claim:

1. The combination of a draft frame detachably and flexibly connectible with a tractor, trailing plowing units having at their 45 front ends vertically fixed transverse horizontal pivotal connections with the frame, vertically adjustable ground wheels normally free to move in the beam lifting direction, a unitary power mechanism having all of its parts operable only in fixed predetermined relation to each other and to the frame, and mutually independent uniformly speeded power transmitting trains acting in 50 uniform succession and connecting the said unitary power mechanism with the several adjustable ground wheels respectively to move them successively with respect to their units, thereby successively lifting the said 55 units upon their ground wheels.

2. The combination of a draft frame detachably and flexibly connectible with a tractor, trailing plowing units having at their 60 front ends vertically fixed transverse horizontal pivotal connections with the frame,

vertically adjustable ground wheels normally free to move in the beam lifting direction, a unitary power mechanism having all of its parts operable only in fixed predetermined relation to each other and to the 70 frame, and mutually independent uniformly speeded power transmitting trains connecting the said unitary power mechanism with the several adjustable ground wheels respectively and acting in uniform succession first 75 to move them successively downward with respect to their units and then to release them to permit them to move successively upward with respect to their units, thereby successively lifting the said units upon their 80 ground wheels and then successively lowering them.

3. The combination of a draft frame detachably and flexibly connectible with a tractor, a diagonal series of trailing plowing 85 units having at their front ends vertically fixed transverse horizontal pivotal connections with the frame, vertically adjustable ground wheels normally free to move in the beam lifting direction, a unitary power 90 mechanism having all of its parts operable only in fixed predetermined relation to each other and to the frame, power transmitting devices connected with the several adjustable ground wheels respectively to move them 95 downward with respect to their units, and means actuated by the said unitary power mechanism for actuating the said devices successively beginning with the one for the foremost unit to lift the units successively 100 and for releasing the said devices successively beginning with the one for the foremost unit to drop the units successively.

4. The combination of a draft frame detachably and flexibly connectible to a tractor, trailing plowing units having at their front ends vertically fixed transverse horizontal pivotal connections with the frame, adjustable ground wheels normally free to move in the beam lifting direction, and a 110 mechanism comprising a power means having all of its parts operable only in fixed predetermined relation to the frame and a series of mutually independent uniformly speeded power transmitting trains actuated by the power means and connected respectively to the plowing units and the wheels to lift the units by pressing down on the wheels, the said mechanism comprising automatically acting means supplemental to the 115 motive means for locking the power transmitting trains in position to cause the units to be held in lifted positions.

5. The combination of a draft frame detachably and flexibly connectible to a tractor, trailing plow units vertically fixedly pivoted at their front ends to the frame for vertical movement, ground wheels vertically movably connected respectively to the units and normally free to move in the beam lift- 125 130

ing direction, a power mechanism on the frame, and mutually independent mechanical power transmitting devices connected respectively for transmitting power from the said power mechanism to the said wheels and plowing units to effect relative movements and thereby lift the units with respect to the ground, each of the said connections serving independently of the others to definitely limit downward movement of the units with respect to the wheels but to leave the units at all times free for upward movement when power is applied.

6. The combination of a draft frame, detachably connectible to a tractor, trailing plowing units having at their front ends vertically fixed transverse horizontal pivotal connections with the frame, ground wheels upon which the plowing units are supported and which are normally free to move in the beam lifting direction power transmitters independent of each other and connected respectively to the said wheels and plowing units to lift the units by pressing down on the wheels, means on the frame comprising a plurality of rotatable eccentric arms, means under the control of the plowman for turning the arms each through a part of a revolution, and devices connected with the said power transmitters and engaging respectively with the said eccentric arms whereby when the arms are turned the transmitters are actuated to cause the plowing units to be lifted and whereby at the end of the said part of a revolution the transmitters are locked against retrograde movement thereby holding the units in lifted positions.

7. The combination of a draft frame detachably connectible to a tractor, trailing plowing units having at their front ends vertically fixed transverse horizontal pivotal connections with the frame, ground wheels upon which the plowing units are normally carried respectively in fixed relation to the ground but with respect to which they are vertically adjustable, power transmitters independent of each other and connected respectively to the said wheels and plowing units to lift the units by pressing down on the wheels, means on the frame comprising a plurality of rotatable eccentric arms, means under the control of the plowman for turning the arms each through a part of a revolution, and devices connecting the said power transmitters respectively with the said eccentric arms whereby when the arms are turned the transmitters are actuated to cause the plowing units to be lifted and whereby at the end of the said part of a revolution the transmitters are positioned so that the line of tension has been moved to the axis of rotation of the arms, the transmitters being thereby locked against retrograde movement thus holding the units in lifted positions.

8. The combination of a wheeled draft

frame, plowing units fixedly pivoted at their front end to the frame for free vertical movement, ground wheels vertically movably connected respectively to the units and normally carrying them in fixed relation to the ground, a motor mounted upon the frame and operating independently of the wheels of said frame, a rotating member to which the said motor is positively connected and which it drives, crank arms mounted on said rotating member and adapted to oscillate upon the same, coöperating devices on the rotating member and the arms adapted to oscillate each of the arms through a part of a revolution in either direction, means for automatically disengaging the said coöperating means at the limits of movement of the arms, and reaches connecting the arms respectively with the plowing units and the ground wheels to lift the units by means of the wheels, the said reaches at the ends connected with the arms each having a portion curved around the said rotating member beyond a line extending between its points of attachment with the described parts. 90

9. The combination with a frame and plowing units fixedly pivoted at their front ends thereto for free vertical movement, of ground wheels vertically movably connected respectively to the units and normally carrying them in fixed relation to the ground, rocking members mounted on the frame, movable means for carrying the rocking members, reaches connecting the said members respectively with the plowing units and the ground wheels to lift the units by means of the wheels, coöperating devices on the rocking members and the said moving carrying means adapted to automatically engage to impart movement to said members 105 in either direction to raise or lower the units, each of the said members in one of its directions of movement being adapted to carry the point of connection of the corresponding reach therewith over and beyond the axis 110 whereby a line drawn through both the connecting points of said reach will be carried through and beyond the said axis, stops for limiting the movement of the members in the last said direction, and means for automatically disengaging the coöperating devices. 115

10. The combination of a wheeled draft frame, plowing units fixedly pivoted at their front ends to the frame for free vertical movement, ground wheels vertically movably connected respectively to the units and normally carrying them in fixed relation to the ground, rocking-arms having a common axis of movement upon the said frame, reaches each connected at one end with one of the arms and each having at the other end control of the relative movement of one of the wheels with respect to the plowing unit, a rotatable power driven member con- 120

125

130

trolling the arms, and pairs of devices on the said member and the said arms adapted to automatically engage one another on the rotation of said rotatable member in one direction to cause the raising of the said plowing units and on the rotation of the said rotatable member in the other direction to cause the lowering of the said plowing units.

10 11. In a plowing mechanism, the combination of a frame, a series of successively acting prime power devices on the frame, a shaft on the frame extending continuously from end to end of said series and rotating 15 from one of its ends to the other when in action, means rotatable concentrically with the shaft for successively connecting its several successive parts, while all of said parts are rotating, to the several prime power devices, a motor carried by the frame in fixed 20 relation to the said shaft, a series of plow units respectively hinged to the frame and each supported on ground engaging devices independently of the others and of the 25 frame, a series of beam lifting devices mounted on said beams respectively, and a connecting device between each of said prime power devices and one of the said beam lifting devices.

30 12. In a plowing mechanism, the combination of a frame, a series of successively acting rotary prime power devices on the frame, a shaft at the axis of, and passing

through, all of said prime power devices, 35 said shaft being rotatable either independently of, or in connection with, all of said power devices, a series of plow units hinged directly to said frame, a series of independent plow lifting devices respectively mounted on the beams of said units, and means 40 connecting each of said prime power devices with one of said unit lifting devices on the beams.

13. The combination of the frame, a series of rotatable cranks mounted on the frame, 45 a series of plow units hinged to the frame, a series of beam lifting devices respectively mounted on the beams of the said plow units and permanently connected respectively to the said cranks, an integral shaft 50 mounted at the axis of the cranks and extending continuously from end to end of said series and rotatable at option either independently of all the cranks of said series, or in engagement therewith a motor 55 on the frame, and devices for transmitting power at option from the motor to the said cranks to actuate the lifting devices mounted on the beams respectively.

In testimony whereof we affix our signatures, in presence of two witnesses.

HERBERT S. HANSON.
CHARLES M. UPHAM.
